CONTROL MECHANISM

Filed June 13, 1931

UNITED STATES PATENT OFFICE

GEORGE A. COMBRIDGE, OF SAN FRANCISCO, CALIFORNIA

CONTROL MECHANISM

Application filed June 13, 1931. Serial No. 544,095.

This invention is a control mechanism for an indicator or display device of that type which embodies a sign element adapted for step-by-step movement, and is particularly applicable to a station indicator mounted in a public conveyance and adapted to successively display the names of the various stops along the route of travel.

It is the object of the invention to provide a control mechanism which is automatically actuated so as to successively shift the sign element, and which in the case of a station indicator for a conveyance may be actuated by movement of a door of the conveyance so as to automatically shift the sign element when the door is actuated at each stop along the route.

It is a further object of the invention to employ the control mechanism in connection with drive mechanism which is adapted to shift the sign element; and more particularly to close an electrical circuit for the drive mechanism by movement of a door, and then automatically and independently of the control mechanism break the electrical circuit when the sign element has been shifted the required distance to display the name of the next succeeding station.

Further objects of the invention will be readily understood from the following description of the accompanying drawing, in which:

Fig. 1 is a front elevation of the shiftable sign element with its casing partly broken away to show the drive mechanism, and the electrical circuit for the drive mechanism being diagrammatically shown.

Fig. 2 is a side elevation of the sign element, with its casing partly broken away.

Figs. 3 and 4 are detail front elevations of the reversing mechanism for the shiftable sign element, respectively showing the sign element at the opposite ends of its travel.

Fig. 5 is a front elevation of the automatically actuated switch of the control mechanism.

Fig. 6 is a plan view of said switch.

Fig. 7 is a front elevation of the manually actuated switch of the control mechanism.

The invention is illustrated in connection

with a station indicator for a public conveyance which has a door A adapted to be opened and closed at each station along the route, the indicator being housed in a casing 1 having sight openings 2 for successively displaying station names 3 on tapes 4 which are adapted for step-by-step movement past the sight openings. The tapes 4 may be wound on rollers 5-6, and may be shifted step-by-step by means of sprockets 7 mounted on shafts 8 and engaging notched edges 9 of the tapes.

The drive mechanism for shafts 8 is shown as an electric motor 12 mounted in casing 1 and driving shafts 8 by suitable trains of reduction gearing shown at 10 and 10a and adapted to shift the tapes 4 in the same direction; and a driving connection 11 is provided between the pair of rollers 5-6 for each tape, with said driving connection including any usual compensating means (not shown) for varying the relative turning of rollers 5-6 in accordance with the varying diameter of the rolled tape on the pair of rollers as the tape is unwound from one roller and wound on the other. The motor 12 is started by closing a switch 13 in an electrical circuit 14, with the switch actuated by movement of door A; and after predetermined rotation of shafts 8 such as is just sufficient to shift tapes 4 so as to display the next succeeding names 3, the circuit 14 is automatically broken so as to provide the desired step-by-step movement of the tapes.

As an instance of this arrangement closing movement of door A is adapted to close switch 13 for initiating rotation of shafts 8, and an auxiliary switch then automatically closes a shunt circuit 14a for the motor 12, and at the same time switch 13 is automatically opened, so that rotation of shafts 8 is continued under control of the auxiliary switch, and this switch is automatically opened after such predetermined rotation of the shafts as will shift the tapes 4 so as to align the next succeeding names 3 with the sight openings 2.

As shown in Figs. 1 and 2, the auxiliary switch may comprise a fixed contact 15 and an insulator disc 16 rotating with one of the shafts 8 and carrying circumferentially spaced contacts 17 forming diametrically op-

posite insulated points 18, so that with the disc turned for alinement of either of the insulated points with contact 15 the shunt circuit 14a is broken, and rotation of disc 16 will engage contact 15 with one of the other of contacts 17 and thus close the shunt circuit 14a for supplying electrical energy to motor 12 until the disc has been turned so as to aline the other insulated point 18 with the contact 15, whereupon the shunt circuit is again broken.

Means are preferably provided for positively stopping rotation of disc 16 immediately upon breaking the shunt circuit 14a, so as to insure exact alinement of contact 15 with one or the other of the insulated points 18, and for this purpose and as shown in Fig. 1, a disc 20 may rotate with the shaft 8 which carries the disc 16, with one or the other of diametrically opposite recesses 21 in the periphery of disc 20 adapted for engagement by a locking pin 22 when the mechanism is at rest. The pin 22 is retracted when the motor 12 is started, thereby releasing disc 20 for rotation of shafts 8, and as soon as the disengaged recess 21 is clear of its locking pin, the said pin is again projected so as to ride upon the periphery of disc 20, ready to drop into the diametrically opposite recess 21 and thereby immediately stop the turning of shafts 8 when the shunt circuit 14a is again broken. The locking pin 22 may be retracted by an electro-magnet 23 in circuit 14, the electro-magnet being energized by closing switch 13 and thus retracting pin 22, and the magnet being then de-energized as a result of the switch 13 being automatically opened immediately after the closing of shunt circuit 14a.

With the mechanism in the position shown in Fig. 1, the main switch 13 and the auxiliary switch 15-17 are open, thereby breaking circuits 14 and 14a so that motor 12 is at rest with one of the names 3 displayed at sight openings 2 and the shafts 8 locked against turning by pin 22 engaging one of the recesses 21. The names 3 displayed at the sight openings 2 indicate the next station along the route of the conveyance, and when that station is reached and door A is operated, the closing movement of the door is adapted to momentarily close and then re-open switch 13. This movement of switch 13 momentarily closes circuit 14 and thereby energizes electro-magnet 23 so as to retract pin 22, and the momentarily closed circuit 14 starts the motor 12 so as to initiate rotation of shafts 8. One or the other of contacts 17 thus engages contact 15 so as to close shunt circuit 14a and thus continue the supply of electrical energy to motor 12 after the momentarily closed circuit 14 is again opened, and the rotation of shafts 8 is thus continued until the motor is stopped by contact 15 alining with the diametrically opposite insulated

point 18, whereupon pin 22 engages the alined recess 21 of disc 20 for stopping shafts 8 with the parts in their normal position of rest and with the shafts 8 having been rotated just sufficiently to display the next 70 succeeding names on tapes 4. The next stop along the route is thus indicated, and when said next station is reached the operation is repeated by the opening and closing of door A.

As shown in Figs. 5 and 6 the switch 13 which is momentarily closed and then reopened by operating the door A, may comprise an operating pin 25 carried by the door and adapted to engage a lever 26 which is pivoted to a bracket 27 mounted alongside the door. The lever 26 carries a bridging contact 28, and the lever is normally turned by a spring 29 so as to engage a stop 30, in which position the contact 28 is clear of spaced contact 31 of the circuit 14 so as to open the circuit, but the lever is adapted to be turned against the tension of its spring and as shown by broken lines in Fig. 6, so that contact 28 bridges the contacts 31 for closing circuit 14. The lever is turned by pin 25 engaging the lever as the door A moves to closed position, and as soon as pin 25 moves beyond the lever responsive to continued movement of the door to its fully closed position engaging its frame B, the spring 29 returns the lever to its normal position clearing contact 28 from the spaced contacts 31, thereby insuring only momentary closing and immediate reopening of circuit 14 each time 100 the door A is closed.

When door A subsequently slides to its open position the pin 25 is adapted to move past the lever 26 without swinging the same, and for this purpose the pin 25 may be pivoted as shown at 33 so that during closing movement of the door an abutment surface 34 of the pin holds the same in projected position for operatively engaging the lever, while during opening movement of the door the pin 25 swings on its pivot 33 and against the tension of a spring 35 so that it clears the lever 26.

The switch 13 thus remains in normal open position during the opening of door A at each station along the route, and is automatically closed and then immediately reopened at each closing of the door when the conveyance leaves the successive stations, thereby providing the previously described step-by-step movement of the sign element so as to automatically display the names of the stations as they are successively approached.

The driving connection for shafts 8 is adapted for reversal when the end of the route is reached and the tapes 4 have been completely unwound from one of their rollers onto the other; and said reversal may be accomplished by employing a motor 12 which is adapted for reverse rotation when a usual 13

cooperating switch 40 in circuit 14 is swung from one operative position to another. The switch 40 may be actuated by one of the tapes 4 reaching its respective limits of travel; and for this purpose the switch may be mounted alongside the tape, with a bell crank operating lever of the switch adapted for engagement of its arm 41 when the tape is completely wound upon its roller 5 as shown in Fig. 3, thereby actuating the switch 40 for reversing motor 12 so that the shafts 8 are rotated in the opposite direction, and at the same time operatively projecting the arm 42 of the bell crank lever so that when the tape 4 is completely wound on its opposite roller 6, as shown in Fig. 4, it is the arm 42 which is operatively engaged for turning switch 40 in the opposite direction so as to again reverse the motor and operatively project the arm 41 for repeating the operation.

The arms 41-42 of the bell crank lever may be respectively engaged by pins 45-45a mounted on tape 4 adjacent its respective ends, with said pins pivoted at 46 so that abutment surfaces 47 hold the pins in projected position and against yielding in one direction while permitting pivotal yielding of said pins in the opposite direction against the tension of springs 48; and the pins 45-45a are mounted in relatively reversed position as shown in Figs. 3 and 4, so that when the tape 4 is completely wound upon roller 5 as shown in Fig. 3, the pin 45 engages arm 41 and thus swings the operating lever of switch 40 to the position shown in Fig. 4, with pin 45 then yielding at its pivot 41 so as to clear the operatively projected arm 42 of the reversing switch as the tape 4 travels in the opposite direction, and when the tape 4 is completely wound upon roller 6 as shown in Fig. 4, the pin 45a engages the operatively projected arm 42 and thus again reverses switch 40 and operatively projects arm 41 as shown in Fig. 3, with the pin 45a yielding at its pivot 46 during subsequent reverse travel of tape 4, so as to clear the operatively projected arm 41.

The invention thus provides for step-by-step movement of a sign element so as to indicate successive stations along the route of a conveyance, with the sign element automatically actuated by the opening and closing of a door of the conveyance at each of the successive stops, and the sign element automatically limited in its movement to the desired step-by-step shifting so as to accurately align the names of the successive stations with a suitable sight opening, and the sign element also adapted for reversal at the end of the route so as to successively display the names of the stations in the reverse order as the route is retraveled in the reverse direction.

In order to operate the indicator in the event that the conveyance goes past a station without the door A being opened and closed, a manually operated switch 13a is

preferably provided in circuit 14 as shown in Fig. 1, and when manually momentarily closed and then automatically reopened is adapted to energize the control mechanism for step-by-step shifting of the indicator as 70 previously described. For this purpose the switch 13a, which is shown at Fig. 7, may be generally similar to switch 13, but, with the pin 25a which actuates its lever 26a adapted for shifting by hand lever 51 instead of by 75 movement of door A. When lever 51 is manually shifted to the broken line position shown in Fig. 7, the lever 26a is swung as previously described so as to close circuit 14, and continued shifting of the lever 51 then 80 disengages the pin 25a from lever 26a so that the latter is returned by its spring to its normal position, thereby breaking circuit 14 momentarily after the closing of said circuit and thus actuating the control mechanism 85 previously described.

In practice a normally closed switch 50 is preferably also provided in circuit 14, and is adapted to be manually opened whenever it is desired to render the control mechanism 90 inoperative. For example if after the sign element has been shifted to display the name of the next succeeding station it becomes necessary to again open and close door A before said next station is reached, the switch 95 50 is manually opened before opening the door so as to render the sign shifting mechanism inoperative; and after the door A is again in normal closed position, the switch 50 is manually closed so that the sign shift- 100 100 ing mechanism is again adapted for operation by momentary closing of either the automatic switch 13 or the manual switch 13a.

I claim:

1. In combination, a vehicle adapted to travel a predetermined route, a sign element, means carried by the sign element for indicating successive stops along the predetermined route, means for shifting the sign element step-by-step so as to successively display the indicating means, and a control for said shifting means including a pivoted lever and an actuating pin carried by a door of the vehicle, the door being adapted for movement in opposite directions to open and close the door, and the pin being adapted to yield so as to clear the lever when the door is shifted in one direction, and being held against yielding so as to engage and actuate the lever when the door is shifted in the opposite direction.

2. In combination, a vehicle adapted to travel a predetermined route, a sign element, means carried by the sign element for indicating successive stops along the predetermined route, an electric motor for shifting the sign element, a switch for starting the motor, said switch including an actuating pin carried by a door of the vehicle and a pivoted lever adapted for opposite swinging to open or close the switch and normally yield-

ably swung in the direction to open the switch, the actuating pin being adapted to engage the lever when the door is moved toward closed position so as to swing the lever for closing the switch and starting the motor, with the actuating pin then moving beyond and releasing the lever as the door is moved to fully closed position so that the lever is swung in the opposite direction for opening the switch momentarily after its closing, an auxiliary switch controlling the motor and adapted to be closed by initial rotation of the motor so as to continue rotation of the motor after the door operated switch is opened, and means for opening the auxiliary switch for stopping the motor after predetermined shifting of the sign element.

3. In combination, a sign element, means for shifting the sign element, and a control for said shifting means including a pivoted lever and an actuating pin carried by an element which is movable in opposite directions, the pin being adapted to yield so as to clear the lever when the movable element is shifted in one direction, and being held against yielding so as to engage and actuate the lever when the movable element is shifted in the opposite direction.

4. In combination, a sign element, a reversible electric motor for shifting the sign element in opposite directions, a switch for reversing the motor, a lever adapted to be swung in opposite directions for operating the reversing switch, and pins carried by the sign element adjacent its respective ends, each pin being adapted to yield so as to clear the lever as the sign element is shifted toward its end which carries the other pin, and being held against yielding so as to engage and actuate the lever when shifting movement of the sign element is completed toward its end which carries the said pin.

In testimony whereof I have affixed my signature.
